UNITED STATES PATENT OFFICE.

AUGUSTE GENDREAU, OF BEMIDJI, MINNESOTA, ASSIGNOR OF ONE-HALF TO
TELESPHORE BEAUMETTE, OF BEMIDJI, MINNESOTA.

LOGGING CAR OR SLEIGH.

1,343,772.

Specification of Letters Patent. Patented June 15, 1920.

Application filed October 9, 1918. Serial No. 257,487.

To all whom it may concern:

Be it known that I, AUGUSTE GENDREAU, a citizen of the United States, residing at Bemidji, in the county of Beltrami and State 5 of Minnesota, have invented certain new and useful Improvements in Logging Cars or Sleighs, of which the following is a specification.

This invention relates to logging appliances, and more particularly to an improved logging car or sleigh adapted to facilitate the loading and unloading of logs on flat cars and logging skids or sleighs or the like, the device being primarily a labor saving 10 and life protecting apparatus reducing the number of the crew necessary to run a logging train to less than one-half, and so constructed as not to obstruct the unloading operation and likewise preventing the logs 15 from being lost by accidentally falling off of the car between a skidway and landing, thereby saving the necessity of employing a crew of men for picking up logs along the road as is at present employed, and by reason 20 of the facility provided in unloading the logs to avoid injury to the crew, thus saving trouble and damage suits incident thereto.

The invention further comprehends the 25 provision of posts or stakes mounted at the side of the car or the like, for instance, the platform of a logging or flat car, having novel means for holding said posts or stakes in upright positions to act in conjunction 30 with the binding chains to hold the logs from accidental displacement or from falling off the car, and means coöperative therewith to release the stakes to permit the latter to swing or drop alongside of the 35 platform from a point distant from the car, so as to permit the logs to be discharged or roll off of the car without possibility of injury to the crew, such parts being of novel construction and relation as will be fully 40 set forth.

With the above and other objects in view, as will appear as the description proceeds, the invention comprises the novel features of construction, combinations of elements and 45 arrangement of parts which will be more fully described in the following specification and then set forth with particularity in the claims appended hereto and which form an essential part of the same.

50 Reference is had to the accompanying

drawings forming a part of this application, wherein similar reference characters will refer to similar parts throughout the several views, in which—

Figure 1 is a side elevation of a portion 60 of the body part of a logging car or sleigh equipped in accordance with the invention, one of the posts or stakes being disposed in an upright or operative position for retaining the logs,

Fig. 2 is a view similar to Fig. 1 with the hingedly supported stake lowered or in operative position,

Fig. 3 is an end view,

Fig. 4 is a fragmentary bottom plan of 70 one of the bunks or bolsters and parts applied thereto,

Fig. 5 is a fragmentary side elevation of the parts shown in Fig. 4, and

Fig. 6 is a fragmentary vertical sectional 75 view of the upper end of one of the posts or stakes.

Referring to the drawings there is shown in detail a portion of the platform of a flat car, a skid, sleigh or the like commonly used 80 for logging purposes and adapted to be transported on wheels or runners in the usual manner. This platform preferably comprises the usual longitudinal or side beams 11 transversely of which are arranged 85 the usual bunks or bolsters 12 upon which the logs are supported longitudinally of the platform, as indicated in Figs. 1 and 3 of the drawings. These bunks are arranged at suitably spaced points and preferably in 90 parallel relation near the center and at the ends of the platform, or any other convenient relation to receive the logs thereon, as shall be found necessary or desirable.

At one side of the platform, in suitable 95 sockets 13 secured to the sides of the platform are upright stakes or posts 14, to each of which a binding chain 15 and a binding chain 16 are secured as through the medium of U-bolts or other fastenings designated 100 generally at 17 and disposed one below the other for a purpose as will presently appear.

The bunks 12 project beyond the sill members 11 at the ends, and attached to the projecting end of each bunk opposite to the 105 stake 14 is an angular supporting plate 18, the horizontal web bearing upon the upper face and the vertical web bearing against one of the side faces of the bunk, the latter web extending below the lower line of the 110

bunk, as shown, said plates being secured in position by U-bolts 19 passed vertically through the bunks and spaced apart at the ends thereof as shown. In this way, the 5 plates are effectively secured in position as shown, although this relation is not essential except that they are preferably disposed upon that side of the bunk adjacent to which the posts coöperative therewith are disposed 10 when in operative position so that the posts will swing away from the bunks when unloading as will be fully set forth. Suspended from the depending end of each plate is a substantially V-shaped hanger 20, the leg 15 portions of which are secured to the plate, while the lower or bight portions thereof are offset away from the plates alongside of the platform of the car or the like and formed with eyes or loops 21 disposed in a vertical 20 plane in spaced parallel relation to the depending portions of the plates.

A post or stake 22 is mounted adjacent to the depending portion of each plate so as to be disposed in a vertical position as when 25 chaining the logs, or to swing downwardly out of the path of the logs alongside of the platform, when unloading the same, and for this purpose, a U-shaped hanger member or band 23 is bolted through the lower end of the 30 post as indicated at 24 in a direction coincident with or parallel to the side of the platform and at right angles to the stirrup-like hanger 20 or gooseneck-like support provided thereby, the lower end or bight portion 35 of each hanger member or band 23 having a restricted open loop 25 pivotally engaging the eye 21 for pivotal or swinging-like movement of the post toward and away from the bunk from a vertical to a horizontal 40 position or vice versa, along the platform in swivel-like fashion.

Each bunk is provided upon the under-side of the projecting end thereof with a transverse groove 26. A plate 32 is bolted 45 to the under face of the bunk and over the end of the groove, the plate being secured in place by the bolts 31. Each plate is formed with upwardly projecting arms 33 in spaced relation and attached at their 50 upper free ends to the bunk as shown at 34. A bolt 27 is slidably supported in the groove 26 by suitable hangers or clips, and limited in movement in one direction by a stop 38, as shown in Fig. 4.

55 To the inner end of the bolt 27 a chain 29 is attached at one end while the other end of the chain is connected as by a bolt 30 to the post 22 at a certain predetermined point. The rod or bolt 27 projects above 60 the plate 32 and between the spaced portions or arms 33 thereof, which latter are designed to accommodate the free end of a binding chain 15. The rod 27 is engaged by the chain after passing over the logs designated at 35 and held from displacement by

retaining the rod against sliding movement, through the medium of a pin or the like 36 suitably suspended by a chain or strap 37 to one of the parts 33, which pin is designed to pass through the rod outwardly 70 of the plate 32, thereby effectively preventing the rod from being withdrawn from the link of the chain 15 while permitting the release thereof by withdrawing the pin when unloading the logs, as will be herein-after set forth. The rod is limited in its movement when released, through the medium of a collar 38 fixed thereon and operating between the bolts 19, the innermost bolt 19, that is the one located adjacent to 80 the depending portion of the plate 18 and the post 22, serving to limit the releasing movement of said rod.

A limiting connection is also provided between each post 22 and the adjacent bunk, 85 such connection comprising a chain or the like 39 connected to the side of the bunk adjacent to which the depending portion of the plate 18 is arranged, as by means of a bolt 40 and to the post 22 above the connection of the chain 39 therewith, as by a U or eye-bolt 41, said chain 39 being adapted to limit the downward swinging movement of the post 22 to a horizontal position alongside of the platform, as is clearly shown 95 in Fig. 2 of the drawings. Acting in conjunction with the binding chain 15, corresponding to the well known bunk or toggle chains as used on lumber cars, is a binding chain 16 as previously set forth, said 100 chain 16 being anchored to the post 14 below the anchoring point of the chain 15, and extending across a recess or groove 42 in the top of the post 22 and through an opening 43 provided in a plate 44 secured to the outer face of the post 22 near 105 its upper end, the free end of the chain being designed to be engaged by a draw-hook 45 mounted upon the outer face of the post below the plate 44 and comprising a 110 stationary part 46 to which the hook is pivoted as shown at 47 so that when the chain is engaged with the hook, and the latter is drawn downwardly, the chain will be drawn taut and held from displacement 115 at its end. The free or lower end of the hook 45 extends between staples 48 and likewise extending through the staples in front of the depending free end of the hook 45, is a pin 50 to retain the hook in 120 locked position.

A third staple 49 is provided through which the pin 50 likewise extends, and is provided with a stop 51 to limit the movement and prevent the entire withdrawal 125 and loss of the pin.

A pull chain or like device 52 is applied to the pin and leads to any distant point away from the paths of the discharging logs, so that the pin may be withdrawn and the 130

hook 45 and binding chain 16 released without danger to the operator.

In the operation of the device, it will be seen that the chain 15 confines all of the logs while the chain 16 confines those below it but not those above it and between the chains 15 and 16. When unloading the pin 36 will be removed to permit movement of the pin 27 to a releasing position. The pin 50 is then withdrawn by pulling the draw chain 52 to release the drawhook 45 and thereby release the chain 16. As soon as the pin 50 is released, the post 22 will swing upon its pivot 25 to a downward position and as the pin 50 is released from a distant point, injury to the operator will be obviated. As the post or stake swings downwardly in its support, it will be limited by the chain 39, but before drawing the chain 39 taut, the chain 29 is drawn taut to release the rod 27, thereby releasing the binding chain 15 and as the post will be out of the way, the entire load will be released and allowed to roll off of the car or sleigh. However, the release rod will not be shifted until the post is alongside the side of the platform, thereby not interfering with the rolling off or discharge of the logs. The posts 22, as before noted, are all arranged to swing longitudinally of the car and will be released simultaneously.

From the foregoing description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus described my invention, what I claim as new, and desire to secure by Letters Patent, is:

1. In a vehicle for hauling logs, a platform, a plurality of bunks in spaced relation transversely of the platform, a log supporting stationary post rising from the platform at one side adjacent to each bunk, a movable post swingingly connected relatively to each of said bunks, a trip hook at the upper end of each movable post, a flexible element connected to each stationary post and adapted to be engaged respectively by said trip hooks, a second flexible element connected at one end to each stationary post, a release pin carried by each bunk, and adapted to be releasably engaged respectively by the last mentioned flexible element, means between the release pins and the movable posts whereby the downward movement of the movable posts withdraws the pins and releases the flexible element engaged thereby,

and means for limiting the downward movement of the movable posts. 65

2. The combination with a platform and a post mounted at one side thereof; of a post mounted at the opposite side and adapted to swing downwardly to a horizontal position 70 alongside of the platform, a binding chain connecting said posts at the upper ends thereof, a second binding chain connecting the upper end of the first named post to the lower portion of the second named post, and 75 release means at the upper end of the second named post adapted to permit falling thereof to release the second binding chain and thus release the load.

3. A car or sled apparatus for hauling 80 logs, comprising the combination with a platform, a plurality of posts mounted along the platform at one side, bunks across the platform adjacent to each post and adapted to support the logs thereon longitudinally 85 of the platform, plates mounted upon the opposite ends of the bunks with respect to the location of the posts, posts positioned adjacent thereto and suspended in the lower ends of said plates, trip hooks at the upper 90 ends of the last named posts, a chain connected to each of the first named posts and engaging one of said trip hooks, a second chain also connected to each of the first named posts, said first named chain being 95 designed to hold the second named posts in upright positions for retaining the logs between the posts, a release pin carried by each bunk for engaging the second named binding chain, connections between the second 100 named posts and said release pin for releasing the second named binding chain when the first named binding chains are released to permit dropping of the posts second named, and means to limit the downward movement 105 of the second named posts.

4. The combination with logging cars or sleighs, having the usual transverse bunks and posts at one side, said bunks projecting from opposite sides of the platform, angular plates mounted upon the projecting ends and one side of the platform opposite to said first named posts and depending therefrom, and a pair of binding chains connected to the first named posts, of a post adjacent to the plate of each bunk, a U-shaped member carried by a lower end of each post last mentioned, a stirrup-like hanger carried by the depending portion of each plate and pivotally engaging the U-shaped 110 member to permit downward swinging movement of the posts second named, said bunks each having a recess at the bottom thereof, a release rod mounted therein, a plate mounted upon the bottom portion of each 115 bunk at the side opposite to the post and plate thereof, said plate having a claw portion between which the second named bind-

ing chain is disposed, a trip hook mounted upon each swinging post near the upper end thereof, said upper end being provided with a transverse recess and an apertured plate 5 through which one of said binding chains is adapted to extend for engagement with the trip hook, a release pin for holding said hook in operative position and adapted to permit release thereof from a distant point, 10 a release rod mounted in the bottom portion of the bunks and extending through the claw of each plate for engagement with a binding chain, means for holding said rod against movement adapted to permit the re-

lease thereof whereby when said trip hook is 15 released, the adjacent swinging post will drop downwardly in a horizontal position adjacent to the side and bottom portion of the platform, a connection between said release rod and post to shift said release rod 20 for disengaging from the chain between the claw, and a connection between the bunk and said swinging post to limit the downward movement thereof.

In testimony whereof I affix my signature 25 hereto.

AUGUSTE GENDREAU.
